UNITED STATES PATENT OFFICE.

EDGAR E. GREVE, OF BELLEVUE, PENNSYLVANIA.

MAKE-UP ROTARY.

Application filed August 1, 1923. Serial No. 655,018.

To all whom it may concern:

Be it known that I, EDGAR E. GREVE, a citizen of the United States, residing at Bellevue, in the county of Allegheny and State of Pennsylvania, have invented certain new and useful Improvements in a Make-Up Rotary, of which the following is a specification.

This invention is for a rotary for use in connection with earth boring tools, and constitutes an improvement on my Patent No. 1,437,757, of December 5, 1922.

It is quite essential that rotaries used in rotary drilling operations be so constructed that one part of the rotary may be fixed against rotation while holding the drill pipe in suspension and during the time another part of the rotary is rotated about the stationary part to screw up or unscrew sections of pipe. At other times, the two parts must rotate in unison.

While various rotaries which operate in this fashion have been devised, the present invention has for its principal object to provide a rotary so constructed as to lend itself to cheapness of manufacture as well as the ready replacement of such parts as may become worn.

The invention may be readily understood by reference to the accompanying drawings, in which:

Fig. 1 is a plan view of a rotary embodying my invention;

Fig. 2 is a section in the plane of line III—II of Fig. 1;

Fig. 3 is a detail view of a slightly modified construction.

Fig. 4 is a section on an enlarged scale on line IV—IV of Fig. 2.

In the drawings, 5 designates a suitable base having a hole 6 therethrough concentrically arranged, about which is a slightly elevated portion or ring on the base, in which is an annular channel 7 in which is a replaceable channel-like race plate 8 in which are conical rollers 9.

Resting on the rollers 9 is an annular spacing block 10 into which is fitted the drive ring 11, the spacing block being secured to the drive ring by feather key 12. The drive ring has a top flange 13, a reduced upper part 14, a further reduced part 15 which is surrounded by spacing block or ring 10, and a still smaller lower end portion 16.

On the top surface of the spacing ring 10

is a channel 10^a in which is a slip ring 17, and surrounding the reduced upper part of the drive ring is a vertical wear ring 18.

Resting on the spacing ring and confined between this ring and the top flange 13 is the gear ring 19 having teeth 20 for engaging the driving pinion 21 on shaft 22.

On the lower end of the drive ring is a removable thrust ring which extends under the edge of base 5 and holds the drive ring against vertical movement upwardly. The outside of the lower part of the drive ring may bear against the walls of the hole 6 in the base through which this portion of the drive ring extends.

Interposed between the spacing ring 10 and the shoulder 11^a on drive ring 11 are shims 23. In the outside of ring 10 are a plurality of recesses 24 into which a locking pin A may be projected to hold the ring 10, and consequently the drive ring 11, against rotation.

Slidably carried in the gear ring is a radially reciprocal locking pin 25^a which may be moved into and out of engagement with notch 25 in flange 13 of the drive ring. By manipulation of this pin, the drive ring may be driven with the gear ring, or the gear ring may be driven alone, depending on the position of the locking pin.

Instead of the locking pin shown in Figs. 1 and 2, other suitable means may be substituted, as shown for instance in Fig. 3, where plug 25^b may be inserted in registering recesses in the flange and gear ring to connect the drive ring and gear ring, this plug being entirely removed when only the gear ring is to be rotated.

In the gear ring is a groove 26 which receives projection 11^a on the block 10, to protect the bearing against the entrance of mud and water. The ring or block 10, in turn, has an annular flange or skirt 27 which protects the lower bearing against the entrance of dirt.

In the drive ring is a reservoir 28 which may be filled with oil through plug 29, and which may be drained by removal of plug 30 at the bottom of drain passage 31. The reservoir has an outlet over vertical wear ring or bearing 18. Inserted at each side of the bearing 18 in the gear ring and in the drive ring are small vertical felt strips 32 for aiding in lubricating the bearing surfaces.

Oil from reservoir 28 draining from the

bearing 18, enters channel 10^a, lubricating the bearing for the gear ring contained therein, and flows down passage 33 leading from a shoulder in the channel 10^a to the cones, where the oil collects in the race plate until it overflows, and lubricates the walls of the hole 6 and the lower end of the drive ring which bears thereon.

Through the upper part of the drive ring 10 is a downwardly tapered opening which terminates in a bell shaped lower opening. In the wall of this tapered opening is a keyway 34. A spider 35 may be nested in this opening, a key 35^a on the spider entering the keyway to hold the spider against relative rotation. The top of the spider is beveled, so that its innermost portion is lower than its outermost portion. This greatly facilitates the insertion of slips or the drive bushing in the central opening in the spider.

This central opening is tapered and a keyway 36 is provided in the wall thereof. Removably fitted in this spider is the drive bushing 37 having a key 37^a for cooperation with the key slot. The top of the key terminates below the top of the bushing, leaving a shoulder at 38. In the drive bushing is a slidable pin 39 tangentially disposed with relation to the drive bushing, this pin being adapted to be projected over shoulder 38 so as to normally hold the drive bushing against vertical movement.

In the gear ring is a tong post receiving socket 40 and in the drive ring is a similar socket 41.

The separate spacing ring and the flanged drive ring confining the gear ring provide a construction which lends itself to relatively cheap manufacture and comparatively light weights, and provides a structure which may be readily taken apart and set up for storage, transportation and replacement and repair of parts.

I claim as my invention:

1. A rotary comprising a base, a drive ring having an integral flanged upper end, a separate removable spacing ring surrounding the driving ring intermediate the ends thereof and connected therewith, a gear ring rotatably carried on said spacing ring and confined between said spacing ring and the top flange of the drive ring, and bearings on the base rotatably supporting said spacing ring.

2. A rotary comprising a base, a drive ring having an integral flanged upper end, a separate removable spacing ring surrounding the driving ring intermediate the ends thereof and connected therewith, a gear ring rotatably carried on said spacing ring and confined between said spacing ring and the top flange of the drive ring, bearings on the base rotatably supporting said spacing ring, and cooperating means on the gear ring and flange for releasably connecting

the gear ring and drive ring in driving relation.

3. A rotary comprising a base, a drive ring having an integral flanged upper end and a depending body portion projecting through the base, a separate removable spacing ring surrounding the driving ring intermediate the ends thereof and connected therewith, a gear ring rotatably carried on said spacing ring and confined between said spacing ring and the top flange of the drive ring, an adjustable removable thrust ring on the lower end of the drive ring below the base for holding the drive ring against upward movement, and bearings on the base rotatably supporting said spacing ring, said gear ring having a laterally extending part whose surface is flush with the top of the drive ring.

4. A rotary comprising a base, a drive ring having an integral flanged upper end, a separate removable spacing ring surrounding the driving ring intermediate the ends thereof connected therewith and vertically adjustable with respect thereto, a gear ring rotatably carried on said spacing ring and confined between said spacing ring and the top flange of the drive ring, bearings on the base rotatably supporting said spacing ring, said gear ring having a laterally extending part whose surface is flush with the top of the drive ring, and cooperating means on this laterally extending portion of the gear ring and drive ring flange for releasably connecting the gear ring and drive ring.

5. The combination with a rotary having a drive ring and a gear ring, said drive ring having a central opening therein, of a spider received in said central opening, a drive bushing removably received in the spider, and locking means in the top portion of the spider for detachably securing the drive bushing in place and operable from the top of the spider.

6. A rotary including a base, a drive ring rotatably carried above the base, a gear ring rotatably carried about the drive ring, a vertical bearing intermediate the gear ring and drive ring, an oil reservoir on the drive ring, and inserted felt strips for conveying lubricants from the reservoir to different parts of the vertical bearing.

7. A rotary including a base, a spacing ring on the base having upper and lower bearing surfaces, bearings interposed between the base and the lower bearing surface, a bearing member in the upper bearing surface, a gear ring on said bearing surface, and a drive ring inserted in the gear ring and spacing ring and slidably connected with the latter, said drive ring having a flange overhanging a portion of the gear ring, and an adjustable thrust ring on the lower end of the drive ring through which all vertical play may be taken up.

8. A rotary having a drive-ring and a gear ring rotatably supported on a base and rotatable relatively to each other, means for locking them against relative movement, a bearing in which said relative movement is effected, a bearing in the base, a lubricant reservoir in the drive ring, and a lubricating feed passage in the drive ring leading

from the reservoir to said first mentioned bearing, said passage being near the outer part of said lubricating chamber whereby centrifugal force will act to keep the oil supply over the feed passage, and an overflow from the first bearing to the second. 10

In testimony whereof I affix my signature.
EDGAR E. GREVE.
